UNITED STATES PATENT OFFICE.

STANWOOD E. FLICHTNER, OF ENGLEWOOD, NEW JERSEY, ASSIGNOR, BY MESNE ASSIGNMENTS, TO COOPER HEWITT ELECTRIC COMPANY, A CORPORATION OF NEW YORK.

STARTING DEVICE FOR GAS OR VAPOR ELECTRIC LAMPS.

SPECIFICATION forming part of Letters Patent No. 733,380, dated July 14, 1903.

Application filed June 28, 1902. Serial No. 113,589. (No model.)

To all whom it may concern:

Be it known that I, STANWOOD E. FLICHTNER, a citizen of the United States, and a resident of Englewood, in the county of Bergen 5 and State of New Jersey, have invented certain new and useful Improvements in Starting Devices for Gas or Vapor Electric Lamps, of which the following is a specification.

The means commonly employed for starting gas or vapor electric lamps of the mercury-vapor type include a main-line switch, one or more inductance-coils in series with the lamp, and a snap-switch arranged in a shunt between each lamp and its own inductance coil 15 or coils. If this arrangement were an invariable one, we should always have the devices mentioned duplicated for each lamp. In places, however, where a number of lamps are to be located near together and subject 20 to the control of the same operator it may suffice to have a single main-line switch and a single snap-switch, together with means for bringing the snap-switch successively into operative connection with the different lamps. 25 Indeed, this action need not be a successive action; but the snap-switch may be brought to operate upon the circuit of any one of a group of lamps at the will of the operator. This is accomplished by the use of an adjustable switch, for example, as will be fully set 30 forth in the specification which follows.

The drawing is a diagram of circuits and connections for starting three gas or vapor electric lamps through the medium of a single snap-switch.

The lamps are shown at 11, the mains at 14 15, the main-line switch at 3, the switches for the several lamps at 3' 3' 3', the reactance-coils at 19 19 19, the snap-switch at 31, the 40 adjustable switch-arm at 32, and a resistance in the same shunt with the snap-switch at 11.

Each of the reactance devices 19 is made up of two coils 20 and 21, the members of each pair being connected in series with each other and the groups being connected in multiple 45 to the main wire 15.

In connection with each of the coils 21 I provide contact-points 27 28 29, with which a switch-arm 26 co-operates. By different ad-

justments of the switch-arm either the entire 50 coil 21 may be included in the circuit or one or more layers of said coil may be cut out. It will be seen that one side of each lamp is connected with a contact-point upon a switch-board 35, whereon the main switch 3, the 55 snap-switch 31, the resistance 11, and the adjustable switch-arm 32 are mounted. The several contact-points which thus form the switchboard-terminals of one side of the lamp-circuit are shown at 36, 37, and 38 in such position that the switch-arm 32 can be caused to co-operate with either one of them at will, a switch-handle 39 being provided for the easy manipulation of the switch-arm. At 40 I show a stop for limiting the motion of the 45 switch-arm.

By an inspection of the diagram it will be seen that each lamp is provided with a separate short circuit between the lamp and its inductance coil or coils and that such short 50 circuit terminates at the switchboard 35 in one of the contact-points 36, 37, or 38. It will also be seen that inasmuch as the switch-arm 32 is itself a portion of the short circuit (which also includes the snap-switch 31 and 55 the resistance 11) either short circuit may be completed through the switchboard by simply bringing the contact-arm 32 into connection with the proper contact-point or terminal. If now it is desired to start one of the 60 lamps, the particular short circuit appropriate to that lamp should first be closed, and the snap-switch 31 should then be operated to cause a quick rupture of the shunt-circuit. The reactance caused in this way in the 65 inductance 19 connected with that particular lamp will cause an impulse of higher potential to be impressed upon the circuit of that lamp, which will thereupon be started into operation. By repeating this process either 70 or all of the other lamps can be started.

The function of the apparatus herein described is the same whether the gas or vapor apparatus on which it acts is intended to give light or to transmit electric currents for any 75 other purpose.

I claim as my invention—

1. The combination with a group or num-

ber of gas or vapor electric apparatuses, each requiring a starting-current of higher potential than that upon which it is to be operated, of a reactance device for each gas or vapor apparatus, a shunt across the circuit between each gas or vapor apparatus and its own reactance device, and a snap-switch adapted to act upon either shunt-circuit at will.

10 2. The combination with a group or number of gas or vapor electric devices, each requiring a starting-current of higher potential than that upon which it is to be operated, of one or more reactance-coils for each device, 15 means for connecting each device with its own reactance coil or coils and means common to all the devices for supplying the starting-current.

20 3. The combination with a group or number of gas or vapor electric devices, each requiring a starting-current of higher potential than that upon which it is to be operated, of a reactance coil or coils for supplying the starting-current to each device, switches controlling the connections of each device with its own reactance coil or coils, a snap or quick-break switch having one terminal adapted to be connected to a corresponding terminal of each device, means for connecting the opposite terminal of the snap or quick-break switch, to the opposite terminal of any selected device, thus forming the shunt upon the reactance coil or coils for that device, and means for operating the snap-switch to break 35 the said shunt by a quick movement.

30 4. The combination with a group or number of gas or vapor electric devices, each requiring a starting-current of higher potential than that upon which it is to be operated, of

a reactance-coil for each device, a shunt across the circuit between each device and its reactance-coil, a snap or quick-break switch having one terminal connected with one side of the said shunt-circuit, means for connecting the opposite side of the snap-switch with any selected device and means for operating the snap-switch whereby the shunt-circuit of the selected device can be broken by a quick movement, thus causing the reactance-coil for that device to start the device. 45 50

5. The combination with a group or number of gas or vapor electric devices, each requiring a starting-current of higher potential than that upon which it is to be operated, of a plurality of reactance-coils in series with each device, means for cutting out one or more layers of one of the reactance-coils, a shunt across the circuit between each device and its reactive coil and a snap or quick-break switch adapted to act upon either shunt-circuit at will. 55 60

6. The combination with a group or number of gas or vapor electric devices, each requiring a starting-current of higher potential than that upon which it is to be operated, of an adjustable inductive resistance in series with each device, a shunt across the circuit between each device and its own inductive resistance, and a snap or quick-break switch adapted to act upon either shunt-circuit at will. 65 70

Signed at New York, in the county of New York and State of New York, this 27th day June, A. D. 1902.

STANWOOD E. FLICHTNER.
